UNITED STATES PATENT OFFICE.

OLIVER C. TALBOT, OF KANSAS CITY, MISSOURI.

ADJUSTABLE CONCRETE FORM.

Application filed January 8, 1923. Serial No. 611,494.

To all whom it may concern:

Be it known that I, OLIVER C. TALBOT, a citizen of the United States, and resident of Kansas City, county of Jackson, State of Missouri, have invented a certain new and useful Improvement in Adjustable Concrete Forms, of which the following is a complete specification.

This invention relates to concrete forms and more especially to forms for laying concrete floors and the like, and the object is to produce a permanent form construction adjustable as to width and depth and hence adapted for meeting all conditions encountered in laying concrete floors.

With this general object in view the invention consists in certain novel and useful features of construction and organization of parts, as hereinafter described and claimed; and in order that it may be fully understood, reference is to be had to the accompanying drawing, in which:-

Figure 1 is a vertical section illustrative of the construction and use of a plurality of form units embodying the invention;

Figure 2 is an enlarged section on the line II—II of Figure 1;

Figure 3 is an inverted plan of the form units, the same being shown on a smaller scale than in Figures 1 and 2;

Figure 4 is a section on the line IV—IV of Figure 1;

Figure 5 is an enlarged section on the line V—V of Figure 1;

Figure 6 is an enlarged section on the line VI—VI of Figure 1;

Figure 7 is a fragmentary perspective view of one of the plate-securing bars;

Figure 8 is a section on the line VIII—VIII of Figure 1; and

Figure 9 is a detail perspective view of the elements of a fastener for securing bars adjustably together.

Referring now to the drawing in detail, 1 indicates a plate of steel or the like, of rectangular form, and provided at one margin with a flange 2. Extending at right angles to the flange 2 and from a point slightly spaced therefrom to the opposite margin of the plate at the inner side thereof, is a pair of bars 3 preferably of U-shape and provided at the upper edges with outwardly projecting flanges 4 fitting flatly against plate 1 and spot-welded or otherwise secured rigidly thereto, each bar constituting a keeper or guide, and having a longitudinal

series of perforations. A plate 5 similar to plate 1, is provided at one margin with a flange 6 corresponding to flange 2, and is adapted in conjunction with plate 1, to span or bridge a suitable space for a part of a concrete flooring F, the flanges 2 and 6 being adapted to determine the adjacent sides of a pair of depending stiffening ribs R for the flooring. The plate 5 is adapted for overlapping more or less the plate 1, and a pair of bars 7 is disposed at the inner side of plate 5 and extend from a point adjacent flange 6 thereof toward the opposite margin of said plate. Said bars are adapted to be fitted in the bars or keepers 3, and are provided with a corresponding series of perforations.

To provide for the interposition of plate 1 between plate 5 and bars 7, the latter are spaced slightly below plate 5 and parallel therewith, and at their ends adjacent flange 6, are rigidly equipped with angle plates 8 which project slightly upward beyond the upper edges of bars 7 and flatly engage the underside of plate 5. These angle plates form laterally widened portions of bars 7, and are spot-welded or otherwise secured to the underside of plate 5, so that said plate and bars 7 shall be of substantially integral construction. The bars 3 and 7 are provided with arms 9, projecting in the same direction as the flanges 2 and 6 respectively, and spaced slightly therefrom, said arms being provided with longitudinal series of perforations as shown.

Narrow rib or beam plates 10 for determining the bottom of the ribs R, are provided with marginal flanges 11, for fitting between the flanges 2 and 6 and the adjacent arms 9 spaced from said flanges as explained, the juxtaposed flanges of the floor plates 1 and 5, and of the rib or beam plates 10, constituting the parts of the form for defining the sides of the ribs or beams, and in order to secure the said juxtaposed flanges together, they are provided with arms 12, preferably in the form of U-shaped keepers like bars 3, and are spot-welded or otherwise secured to said flanges 11. The arms 9 extend through said arms or keepers 12, which, like the arms 9 are preferably provided with a series of perforations for registration with certain of the perforations of the arms 9. Any suitable fastening devices may be employed to secure the bars 3 and 7 together at the desired points of adjust-

ment, and to secure the arms 9 and 12 together at the desired point of adjustment. The preferred construction for accomplishing this purpose is a staple-like member 13 provided with notches 14 in the inner sides of its legs, and a notched key member 15 adapted to span the space between the legs and engage the notches 14 thereof. The construction thus far described with the addition of bars 16 (one in the form of a keeper and the other of plain bar form) constitutes one complete form unit, a number of such units being required to lay a floor. The unit described obviously is adjustable to accommodate or span spaces slightly exceeding the width of plate 1, up to a width slightly less than the combined width of members 1 and 5, and the relation between the flanges of said plates and the flanges of the beam plates is such that the depth of the beams can be likewise varied by adjustment of arms 12 on arms 9.

In arranging the units, they are disposed so that the adjacent rib or beam plates overlap to define the bottom of a rib or beam, the keeper bar 16 of one beam plate receiving the plain bar 16 of the cooperating overlapping rib or beam plate, which bars are then secured together, as by bolts 17 and nuts 18, as shown by Figure 6.

In Figure 1, a complete unit of the character described is shown and segments of two adjacent or cooperating units appear in cooperative relation with the complete unit, that is to say adjacent units are arranged with their respective plates 10 arranged in overlapping relation so as to constitute in conjunction therewith the bottoms of the ribs or beams, the flanges of the adjacent units constituting the forms for the opposite sides of the beams.

Each unit may be provided with two sets of fastening bars or keepers as shown by Figure 2, or may be provided with a single set or with three or more sets as will be readily understood, and in Figure 2, it will be seen that juxtaposed units spanning the space between the same ribs or beams, are adapted to be arranged in overlapped relation, it being understood in this connection that the overlapping of the various plates will result in irregularities or jogs in the surface of the concrete after the forms are removed, but that this is not objectionable as a coating of plaster or the like will provide for a smooth and uniform finish if such is desired.

In the event a space wider than the combined widths of plates 1 and 5, bars can be employed to bridge the span between bars 3 and 7 and be secured thereto and an unflanged or flat plate be placed thereon between plates 1 and 5, or it may overlap and rest on said plates.

It will be apparent from the foregoing

that a construction of the character described dispenses with the necessity of using the multitude of struts or braces necessary to support the conventional type of concrete floor forms, and that the work and cost of laying floors will be reduced. The first cost of the forms will be greater than that of the conventional type, but they can be used repeatedly and will meet all conditions as to depth or thickness and distance between ribs or beams.

From the above description it will be apparent that details of construction and arrangement of parts may be varied without departure from the principle of construction involved or from the spirit and scope of the appended claims, and that the forms may be employed in concrete work other than flooring.

I claim:

1. Concrete form construction, comprising a plate, a bar secured to one side of the plate, a second plate for cooperation with the first-named plate in spanning space, and a bar rigid with and spaced from the second plate for underlying the first plate when the same is overlapped by the second plate, and fitting sidewise against the bar of the first plate; said plates having projecting flanges at the edges adjacent the remote or outer ends of said bars, and means for securing the said bars rigidly together.

2. Concrete form construction, comprising a plate, a bar secured to one side of the plate, a second plate for cooperation with the first-named plate in spanning space, and a bar rigid with and spaced from the second plate for underlying the first plate when the same is overlapped by the second plate, and fitting sidewise against the bar of the first plate; said plates having projecting flanges at the edges adjacent the remote or outer ends of said bars, and means for securing the said bars rigidly together, in combination with plates having flanges fitting flatwise against the flanges of the first and second plates, and means for securing the last-named plates in rigid relation to the said first and second plates.

3. Concrete form construction, comprising a plate, a bar secured to one side of the plate, a second plate for cooperation with the first-named plate in spanning space, and a bar rigid with and spaced from the second plate for underlying the first plate when the same is overlapped by the second plate, and fitting flatwise against the bar of the first plate; said plates having projecting flanges at the edges adjacent the remote or outer ends of said bars, and means for securing the said bars rigidly together, in combination with plates having flanges fitting flatwise against the flanges of the first and second plates, arms rigid with and projecting respectively from the outer ends of

- the first-named bars and parallel with and spaced from the flanges respectively of the first and second plates and fitting flatly against the flanges of the third plates, and 5 arms secured to the last-named flanges and to the arms projecting from the first-named bars.
4. In a concrete form construction, an angle plate, and an angle bar arranged within 10 in the angle of the plate with its arms parallel with but slightly spaced from the respective sections of the plate, the angle bar adjacent its corner being rigidly secured to the angle plate.
- 15 5. In a concrete form construction, an angle plate, and an angle bar arranged within the angle of the plate with its arms parallel with but slightly spaced from the respective section of the plate, the angle bar 20 at its corner having a widened portion engaging and rigidly secured to the angle plate.
6. In a concrete form construction, an angle plate, an angle bar arranged within
- the angle of the plate with one of its arms 25 rigidly secured to the respective or adjacent portions of the angle plate and its other arm parallel with but slightly spaced from the adjacent or respective portion of said plate, in combination with an angle plate having 30 one arm fitting between the spaced arm of the bar and first-named plate, and an arm fitting against and parallel to said spaced arm and secured to said interposed arm of the second angle plate, and means to secure 35 said last-named arms together.
7. In a form, a sheet metal angle plate and a bar of correspondingly angular form, the corner of the bar fitting within the angle 40 of the plate and the arms of the bar extending parallel with and spaced from the respective portions of the plate; and angle plates permanently secured to the corner of the bar and to the corner of the plate.

In witness whereof I hereunto affix my 45 signature.

OLIVER C. TALBOT.
